LUTHER D. LOVEKIN, OF WYNNEWOOD, PENNSYLVANIA, ASSIGNOR TO KITSON COMPANY, OF PHILADELPHIA, PENNSYLVANIA, A CORPORATION OF WEST VIRGINIA

THERMOSTATIC CUT-OFF VALVE

Application filed May 24, 1928. Serial No. 280,192.

The general object of the present invention is to provide a thermostatic valve specially devised for use in connection with fluid heaters and in particular domestic water heaters and adapted to cut off the supply of fuel to the heater burner when the temperature in the heater attains a predetermined maximum.

My improved valve is intended for use as a safety or cut-off device, and not as a thermostatic temperature regulator, and is characterized by the special provisions made for subjecting a fusible metal part employed in the valve mechanism to the temperature of the liquid in the heater with which the valve is used without exposing said part to contact with the water. To this end I provide a casting body with a shank extension which is adapted to extend into a heater tank, and I mount said fusible part within the portion of said extension located within the heater tank.

A preferred form of my improved valve is further characterized by features of construction and arrangement adapting the valve to be connected to a heater tank structure through its hot water outlet pipe, or other pipe connection, so that the valve may be applied to existing types of heaters not initially designed for use with such a valve at a minimum of cost and trouble in applying the valve. For this purpose I form the shaft extension of my improved valve so that it may be readily secured in a T forming a part of the hot water outlet or other heater pipe connection, and so that it comprises a slender portion adapted to pass into the body of the heater through the T and through the nipple connecting the latter to the heater tank.

The various features of novelty which characterize my invention are pointed out with particularity in the claims annexed to and forming a part of this specification. For a better understanding of the invention, however, and the advantages possessed by it reference should be had to the accompanying drawings and descriptive matter in which I have illustrated and described preferred embodiments of my invention.

Of the drawings:—

Fig. 1 is a sectional elevation of the cut-off valve and part of the heater shown in Fig. 2;

Fig. 2 is an elevation of a water heater and its improved cut-off valve; and

Fig. 3 is a sectional view of a portion of a valve of modified form.

In the drawings and referring first to Fig. 2, A represents a conventionally illustrated automatic water heater having a hot water outlet B and heated by fuel supplied to a burner (not shown) through a fuel supply pipe C. In the construction shown in Fig. 2, the supply of gas through the pipe C to the burner is normally regulated by a thermostatic valve D, which may be of any usual form for decreasing or increasing the fuel supply as the temperature of the water in the boiler increases to, or falls below a predetermined value.

In accordance with the present invention the supply of gas through the pipe C is also controlled by an automatic shut-off valve E. The valve E comprises a casing body having formed in it a passageway comprising an inlet chamber portion E' and an outlet chamber portion E² separated by a partition in which is formed a valve seated port E³. Flow through the port E³ is controlled by a valve F. As shown, the valve F is formed with a cylindrical extension F' slidably received in and guided by a housing part G shown as threaded into an aperture in the valve casing body in line with the port E³.

The valve F is arranged to have a loaded or valve closing tendency which is due, in the construction shown in Figs. 1 and 2, in part to gravity, and in part to the action of a spring H mounted in the housing G. In the arrangement shown in Figs. 1 and 2, this valve closing tendency is normally opposed, and the valve is held in its open position by means comprising a fusible metal abutment I and a strut formed in part by a stem portion F² of the valve F, and in part by a rod J in line with the valve stem F² and interposed between the latter and the fusible abutment I. The fusible abutment I is located in a hollow shank extension of the valve casing. As

shown, this shank extension comprises an integral tubular extension E^4 of the valve casing body, a tubular part K , and a tubular abutment receiving member L . Advantageously, and as shown, the member K is in the form of a tube having externally threaded ends, one of which is screwed into a threaded socket formed in the end of the valve casing shank extension E^4 , and the other end of which is threaded into the member L which is in the form of an internally threaded sleeve. The end of the sleeve L remote from the valve casing is closed, in the construction shown in Fig. 1, by a plug M having a tubular externally threaded portion which is screwed into the sleeve L . The fusible abutment I is in the form of a disc of fusible metal having the desired melting point and is shown in Fig. 1 as bearing at its margin against the adjacent 20 end of the tubular portion of the plug M . As shown, the pipe connection to the outlet B comprises a T or fitting part B' having a through passage coaxial with the outlet B and communicating with the latter through 25 a nipple B^2 , and having a lateral outlet B^3 to which the hot water service pipe B^4 is connected. As shown, the end of the shank extension portion E^4 of the valve casing body is externally threaded and is screwed into the 30 upper end of the through passage in the T fitting B' , and the tubular portion K of the casing extension extends axially through the T fitting B' and through the nipple B^2 into the heater tank A . The fusible metal abutment I may thus be located two or three 35 inches or so below the top wall of the tank, so as to be directly responsive to the temperature of the water in the tank, and practically free from any direct cooling effect due to heat 40 radiation from the tank wall or fitting parts or to gas flow through the valve thoroughfare.

It will be observed that the parts M , L , K and E^4 unite to form an extension of the 45 valve casing body comprising a chamber space communicating at one end with the passageway through the valve casing body, but closed at its other end and that this space receives the fusible metal abutment I , and the 50 major portion of the strut formed by the valve stem F^2 and rod J . To guard against any objectionable collection of tar condensing out of the fuel gas in the lower portion of the chamber space in the shank extension, a 55 washer E^5 , fitting closely about the valve stem F^2 , is mounted in the valve casing between the outlet passage E^2 and the space in the chamber shank extension of the valve casing.

60 With the described construction, the fusible metal abutment I is located within the tank body so as to be directly responsive to the temperature of the water in the heater tank. If, through a failure of the thermostatic valve 65 D , or for any other cause, the heater water

temperature rises to the maximum fixed by the composition of the abutment I , the latter softens and the closing tendency of the valve F due in the construction shown, as previously explained, in part to gravity and in part to the spring H , causes the valve to close. If the valve closing tendency is made as great as I consider ordinarily preferable, the valve will ordinarily seat before the disc I melts. In such case, the rod J punches a plug out 70 of the softened abutment I , and thereby converts the latter from a disc into a washer. 75 In some cases, however, the rise in temperature to which the disc I is subjected may be sufficient to completely melt the latter, in which case the resolidification of the metal, when its temperature is subsequently reduced, will anchor the rod J in the plug M . With the described construction, however, this is 80 of small consequence, since the plug M may be easily separated from the sleeve L when the cut-off valve is removed, as is necessary in any event for the replacement of the fusible metal disc I . When the plug M is removed, the rod J , if anchored to the plug, may be 85 loosened, and the fusible metal in contact with the plug M or rod J may readily be eliminated by heating the parts in a gas flame, or otherwise, to the temperature required to melt the metal employed in the disc I . 90

95 As will be readily apparent, with the mechanism shown in Figs. 1 and 2 the fusible metal abutment I , while out of contact with the water in the tank or boiler with which it is associated, is so disposed that it is maintained at approximately the same temperature as the water, and is not subjected to any significant cooling either by radiation from the external portions of the valve mechanism or the fitting in which it is mounted, or by the cooling effect of the fuel gas flow through the valve thoroughfare.

100 The valve construction shown in Figs. 1 and 2, obviously may be readily connected to an existing water tank or boiler installation not initially devised with intent for such use, since such installations ordinarily comprise pipe connections to the tank or boiler similar in character to those formed by the pipe fitting parts B' , B^2 and B^4 . The shank extension portion K may well consist of a section of ordinary tubing of an external diameter of a half an inch or so, which is small enough to pass through the T B' and nipple B^2 without objectionably obstructing the flow of water therethrough. If the application of the 105 type of valve mechanism shown in Fig. 1 to different installations, or to different types of tanks or boilers requires the use of shank extensions of different lengths, such length variations may be provided without other changes in the apparatus than suitable variations in the lengths of the tube sections K and rods J employed.

110 115 120 125 130 Where circumstances permit the use of a

cut-off valve having its shank extension threaded directly into an aperture in the tank or boiler wall with a portion of the shank extension projecting into the tank or boiler, I may advantageously employ the form of my invention shown in Fig. 3.

The casing of the valve EA shown in Fig. 3 differs from that of the valve shown in Figs. 1 and 2, in that the entire shank extension is formed by an integral hollow extension portion E⁴⁰ of the valve body. The end of the bore of the shank extension is closed by a screw plug MA, which may be brazed in place, since in this form of my invention the fusible metal abutment I may be replaced without removing the plug MA. As shown, the shank extension E⁴⁰ has an intermediate externally threaded portion screwed into a threaded opening in the wall AA of the tank or boiler with which the valve is used, and is so proportioned that the fusible abutment I is located at a suitable distance from the wall AA at the inner side of the latter.

In the valve shown in Fig. 3, the fusible metal disc I is mounted in a cartridge-like casing comprising a cup-shaped body member O, and a gland-like member P threaded in place in the otherwise open end of the member O and forming a guide for a strut member JA in the form of a rod having a head J' at its outer end, which is normally engaged, within the outlet chamber E² of the valve EA, by the aligned stem F² of the cut-off valve member. The member O is formed intermediate its ends with an internal circumferential shoulder against which the disc I bears at its edge. The adjacent end of the rod JA bears against the center of the abutment disc I. As shown, the member J is also guided intermediate its ends by a washer Q, and is guided adjacent its upper end by a washer member E⁵.

The diameter of the valve controlled port E² is made greater than the external diameters of the washer members E⁵ and R and cartridge casing parts O and P. In consequence, when the melting or perforation of the abutment member I makes the replacement of the latter necessary, such replacement may be effected by removing the control valve from the valve casing EA, and then withdrawing the rod J from the valve casing through the port E². The head J' on the upper end of the rod JA facilitates the withdrawal of the latter. A pin R passing through the rod JA beneath the top of the gland member P prevents the cartridge casing for the abutment I from separating from the rod JA when the latter is being removed. Similar pins R may extend through the rod JA beneath the washers E⁵ and R, though this is not essential, since the removal of the rod JA and cartridge casing parts O and R, necessarily effects the removal of the washers Q and E⁵.

While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.

Having now described my invention what I claim as new and desire to secure by Letters Patent is:—

1. The combination with a fluid fuel burning water heater and its fuel supply connection, of a pipe connection to the heater comprising a T and a nipple through which one end of the through passage of the T opens to the water space of the heater, a fuel cut-off valve comprising a valve casing body portion and a hollow shank, the latter being attached to said T and comprising a slender portion extending through said through passage into the heater water space, said casing body portion being formed with a passageway forming a part of said fuel supply connection, a valve controlling said passageway and tending to move from an open position into a position in which it closes said passageway, and means normally holding said valve in its open position comprising a fusible metal abutment mounted in a portion of said shank located within the water space and strut means extending between said abutment and said valve.

2. In combination with a valve casing which comprises a body portion formed with a passageway through it, and a shank extension from said body portion with a passage therein extending from the end of said shank remote from the body portion to said passageway, a part detachably secured to said shank end and normally closing the corresponding end of said passage, a valve controlling said passageway and tending to move from an open position into a position in which it closes said passageway, means normally holding said valve in its open position comprising a fusible abutment mounted in said passage adjacent its said end and strut means extending between said abutment and said valve, said strut means comprising a section insertible with said abutment into said shank through the said end of the latter when said detachable part is removed.

3. In combination with a valve casing which comprises a body portion formed with a passageway through it and a shank extension from said body portion with a passage therein extending from the end of said shank remote from the body portion to said passageway, a part detachably secured to said shank end and normally closing the corre-

- sponding end of said passage and formed with a cavity opening to said passage, a valve controlling said passageway and tending to move from an open position into a position in which it closes said passageway, means normally holding said valve in its open position comprising a fusible abutment engaging said part at the margin of said cavity, and strut means extending between said abutment and said valve and comprising a section separable from said valve member and adapted to enter said cavity when said abutment softens and permits such entrance.
4. In combination with a valve casing which comprises a body portion formed with a passageway through it and a shank extension from said body portion with a passage therein extending from the end of said shank remote from the body portion to said passageway, said shank comprising aligned sections threaded together, of which the end section is in the form of an internally threaded sleeve, the section adjacent thereto is in the form of a tube having one end threaded into said sleeve, and a section more closely adjacent to said body portion is in threaded engagement with the other end of said tube and has an externally threaded portion larger in external diameter than said sleeve, a plug threaded into the second end of said sleeve, a valve controlling said passageway, and means normally holding said valve in its open position comprising a fusible abutment mounted in said sleeve and supported by said plug, and strut means extending between said abutment and said valve and comprising a section separable from the valve and insertible in and removable from said shank through the said end of the latter when said plug is removed.
5. In combination with a valve casing which comprises a body portion formed with a passageway through it and a shank extension from said body portion with a passage therein extending from the end of said shank remote from the body portion to said passageway, said shank comprising two aligned sections of which the one more remote from said body portion is smaller in external diameter than the other of said sections, means connected to the end of said more remote section most remote from said body portion for closing the corresponding end of said passage, a valve controlling said passageway, a fusible abutment mounted in said passage and supported by said means, and strut means extending between said abutment and said valve and holding said valve in its open position.
6. In combination with a valve casing which comprises a body portion and a hollow shank and is constructed for attachment to the wall of a tank with a tank-entering portion of said shank projecting into the tank through an aperture in said wall, said casing being formed with a passageway in said body portion, a valve controlling said passageway and normally tending to move from an open position into a position in which it closes said passageway, a valve stem connected to said control valve, and means normally holding said valve in its open position comprising a fusible metal abutment located in said tank-entering shank portion and a separate strut normally contacting with and extending between said abutment and said valve stem.
- Signed at New York city, in the county of New York and State of New York, this 23rd day of May, A. D. 1928.
